UNITED STATES PATENT OFFICE

EDMUND H. LUNKEN AND CHARLES M. CONKLIN, OF CINCINNATI, OHIO, ASSIGNEES, BY
DIRECT AND MESNE ASSIGNMENTS, TO THE LUNKEN STEEL WINDOW CO., A CORPO-
RATION OF OHIO

SELF-CLOSING WINDOW.

No. 902,978.

Specification of Letters Patent.

Patented Nov. 3, 1908.

Application filed May 22, 1907. Serial No. 375,080.

To all whom it may concern:

Be it known that we, EDMUND H. LUNKEN and CHARLES M. CONKLIN, citizens of the United States, residing at Cincinnati, Ohio, ⁵ have invented certain new and useful Improvements in Self-Closing Windows, of which the following is a specification.

Our invention relates to improvements in self-closing windows, and is designed more especially for use in connection with fire-proof or metallic windows, such as disclosed in an application filed by us Nov. 22, 1906, Serial No. 344643, though not necessarily limited in this respect. We have shown it ¹⁰ as embodied in the improved form of sash which forms the subject of another application filed by us on the 14th day of March ¹⁵ 1907, Serial No. 362463.

The object of the invention is to provide ²⁰ among other things in connection with vertically moving counterbalanced window sashes, simple and durable means for effecting the automatic closing of the upper and lower sashes which shall be reliable and certain in its action.

With these and other objects in view the invention includes the various features of construction and arrangement and combination of parts hereinafter described and particularly pointed out in the appended claims. ³⁰

An embodiment of the invention is shown in the accompanying drawings, in which,—

Figure 1 is a front elevation showing a window frame with its accompanying upper ³⁵ and lower sashes. Fig. 2 is an enlarged sectional detail showing the upper and lower corners in section and with the central portion of the frame broken away. Figs. 3 and 4 are detail views on a larger scale, of the bracket and lever used in connection ⁴⁰ with the closing device for the upper sash. Fig. 5 is a sectional perspective view of a portion of the frame of the lower sash. Fig. 6 is a detail view of the fuse plate, and ⁴⁵ Figs. 7 and 8 are detail views of the connection between the steel sash cord and the chain.

Referring by reference characters to this drawing, the numeral 1 designates the window frame or casing, and 2 and 3 the upper and lower sashes respectively. The frame as shown is supposed to be constructed of metal, as also are the sashes, the latter being provided with guiding edges or strips 4 de- ⁵⁰ signed to slide in corresponding grooves or

ways in the window frame. In the form shown in the drawing, these strips 4 are shown as hollow and seated in grooves or channels formed by the projecting flanges ⁵ 60 of the sash.

The upper sash is normally counterbalanced by weights 6 traveling in the weight pockets or guides of the window frame and connected to the upper sash by cords of steel or like incombustible material as shown at 7. ⁶⁵

Within each weight pocket near its upper end is located a bracket 8 to which is pivoted a bell crank lever 9, the bracket having its angular turned part secured to the frame in any suitable manner as by riveting. Each ⁷⁰ lever has one arm extended vertically and is provided at its end with a link 10 extending through an opening in the frame. Two cords 11 extend from these links towards each other and are connected together by a ⁷⁵ fusible connection 12.

An auxiliary weight 14 has an eye 15 engaged by the other or short arm of each bell crank lever, and it will thus be seen that as long as the fusible connection above referred ⁸⁰ to is intact and the short arms of the levers in horizontal position, the auxiliary weights will be suspended from the levers. Should, however, the fusible connection be melted the bell crank levers will be free to rock into ⁸⁵ position to allow the weight to become detached and fall upon the main or counterbalancing weights, when the combined weight of the two sets will overbalance the upper sash and cause it to be immediately ⁹⁰ closed.

In order to insure that each auxiliary weight shall drop equally upon the main weight, it is provided with a vertical passage through which the sash cord passes. ⁹⁵

The lower sash is counterbalanced by weights 16 which are connected to cords 17 passing over pulleys in the top of the frame in the ordinary manner. These cords extend down within the hollow space formed ¹⁰⁰ between the edges of the sash and the side guide strips and are connected by a detachable connection (also located in this hollow space) with chains 18. This connection preferably comprises a metal tube 18' into one end of which the end of the steel cord is braced or soldered, and a hook 19 which has its shank similarly secured in the other end and which engages a link of the chain. This forms a very convenient detachable and ¹⁰⁵ ¹¹⁰

adjustable connection. The chains are passed through a hole 20 in the channel iron of the sash and into the space or channel in the lower rail 21, in which is located a fuse plate 5 22 to which the end of the chains are fusibly connected.

The plate or member 23 which covers the space 21 being removable affords access to the fusible connection. Thus in case of excessive heat the fusible connection will melt 10 and the release of the chains will disconnect the weight and sash allowing the latter to at once close by gravity.

Having thus described our invention what 15 we claim is:—

1. In combination, a window frame or casting, balancing weights therein for the sash, cords connecting the same to the sash, brackets secured within the frame near the upper 20 corners, a bell crank lever pivoted to each bracket and having a vertically and a horizontally disposed arm, an auxiliary weight

suspended from the horizontal arm of each lever, and a connecting means including a fusible portion and extending through the 25 walls of the frame and directly connecting the vertical arms of said levers, substantially as described.

2. In combination, a window frame, counter-balancing weights therein, a sash having 30 hollow side frame members, cords connected to said weights and extending within said side members, a sleeve connected to the end of each cord, a hook carried by each sleeve, a chain engaging each hook and fusible 35 means for holding the chains, substantially as described.

In testimony whereof, we affix our signatures in presence of two witnesses.

EDMUND H. LUNKEN.
CHAS. M. CONKLIN.
